UNITED STATES PATENT OFFICE.

JOHN H. JOHNSON, OF OMAHA, NEBRASKA.

BUILDING-SCREED.

1,259,020.

Specification of Letters Patent. Patented Mar. 12, 1918.

Application filed December 5, 1917. Serial No. 205,521.

To all whom it may concern:

Be it known that I, JOHN H. JOHNSON, a citizen of the United States, residing in the city of Omaha, county of Douglas, and 5 State of Nebraska, have invented certain new and useful Improvements in Building-Screeds, and have described the same in the following specification, illustrated by the accompanying drawings.

10 My invention relates to that class of screeds which are commonly affixed to concrete, tile or brick walls or partitions of buildings, before plastering, as grounds for the subsequent attachment of casings, mold- 15 ings and other wall strips, and which individually comprise a block of fibrous or other suitable material. It is the main object of the invention to simplify the construction, and reduce the cost of manufac- 20 ture, of such screeds, while preserving their effectiveness; and in general to produce a superior screed of the specified class. To accomplish this object I make my improved screed in the form of an oblong flat plate 25 which has terminal shoulders and is grooved in a special manner.

In said drawings, illustrating the best manner in which I have contemplated applying the principles of the invention, Figure 1 is a plan of a screed which is constructed in accordance with these principles. Fig. 2 is a central transverse section of the same on either of the section lines 2-2 in Fig. 1. Fig. 3 is a sectional elevation showing in broken and full lines two of my improved screeds mounted in contiguous walls of a room as supports for picture molding. Fig. 4 is a like view of the same screeds applied to the same walls 35 as supports for a chair rail or casing. Fig. 5 is a similar view showing several of my improved screeds, some of which are seated in the same walls as supports for base molding, or mop-boards, and others in a concrete floor as supports for floor joists.

45 My improved screed, whereof a specimen is shown separately in Figs. 1 and 2, is denoted generally by the numeral 6. It is of wood or other suitable material, and is 50 formed from a single thin oblong block, or solid blank of uniform cross section. It has two parallel sides or edges 7, which are uniformly and symmetrically beveled from its wider back side 8 to its narrower front side 9, as shown. It has spaced longitudinal channels 10, which are sunk in

the side 8 to a uniform depth approxi- 60 mately equal to half the thickness of the block, and are preferably non-central in the sense of being partitioned apart by the middle broad longitudinal side strip 23 be- 65 hind or under the groove 11. To prevent warping, it has a central longitudinal groove 11 sunk in the front side 9 to a uni- 70 form depth nearly equal to one-third the thickness of the block. It has in its front side the transverse central channel 12, which is of uniform depth and inter-communicates immediately with the channels 10. It has also, near each end of the screed, 75 a transverse square shoulder 13, formed by removing from the front face of the blank sufficient material to uncover the chan- 80 nels 10.

The described screed is completely 75 formed from the described blank by sub- jecting the latter to two successive simple operations which are performed by run- 85 ning the blank first longitudinally through a molding machine, and then crosswise 80 through a gang dadoing machine. By run- 90 ning the blank through the molding ma- chine the edges 7 are beveled and the longi- 95 tudinal channels 10 and groove 11 are ex- 95 cavated; while by running the same trans- versely through the dadoing machine the cross channel 12 is excavated and the ends 100 of the blank are cut down and excavated to form the shoulders 13. A plurality of screeds of this kind may be formed end to end from a continuous blank strip of uni- 105 form cross section, and may be severed from each other, in the process of manufacture, by means of a circular saw of sufficient diameter, mounted in the middle of the dado head. When this convenient method is pur- 110 sued, the adjacent shoulders 13 of abutting screeds are opposite side walls of a trans- verse channel 22 formed partly and equally in each screed. When completely formed, the screeds should be dipped in creosote or other preservative before using.

The use of my improved screed in connec- 105 tion with vertical building walls is illus- trated in Figs. 3, 4 and 5; and in connec- 110 tion with horizontal flooring, in Fig. 5. Patches or deposits 14 of plaster of Paris or similar adhesive material are applied to the wall 21 as shown. To these the screeds are then applied with pressure toward the wall in positions wherein their faces 9 are flush with the proposed face 15 of the plas-

ter which is to be applied. By this pressure a portion of the adhesive material 14 is forced into the channels 10 and 12 and the half channels 22, where it hardens and 5 clenches the screeds permanently to the walls. The plastering 15 is then applied to the wall 21 in the customary manner, so as to overlap the beveled edges of the screeds as well as all the exposed surface of the 10 hardened adhesive material. The moldings 16 are then placed in position and secured contactually to the screeds by the nails 17. Fig. 5 further illustrates the similar manner in which my improved screeds are used 15 in connection with a concrete floor 18 for the support of the joists 19 under the wooden floor 20.

I claim as my invention—

1. A building screed of the specified class, 20 comprising an oblong block having non-central longitudinal channels in one side thereof, a central longitudinal groove and a transverse channel in the opposite side thereof, and openings from the longitudinal 25 channels into the transverse channel.

2. A building screed of the specified class, formed of a thin oblong block and comprising a plurality of longitudinal channels in the back side of the block, a central channel 30 extending continuously across the face

of the block, and opening immediately into each of the longitudinal channels.

3. A building screed of the specified class, formed of a single oblong block, and having 35 two opposite beveled edges, longitudinal channels sunk in one side of the block, a longitudinal groove and a transverse channel formed in the opposite side of the block, and openings from the transverse channel into the longitudinal channels respectively. 40

4. As a new article of manufacture, a building screed of the specified class, formed of an oblong block and comprising two beveled edges, a plurality of longitudinal channels in the back side of the block, a longitudinal groove and a transverse channel 45 which are formed in the front side of the block, and openings from the longitudinal channels into the transverse channel.

5. A building screed of the specified class, 50 formed of a single oblong block, and having longitudinal channels in the back side thereof, terminal channels and a central channel which are formed transversely and continuously in the front side of the block, and an 55 opening from each of the longitudinal channels into each of the transverse channels.

Witness my signature at Omaha, Nebraska, November 30th, 1917.

JOHN H. JOHNSON.
